UNITED STATES PATENT OFFICE.

GUY F. BRISENDINE, OF DECATUR, ILLINOIS.

CHECK AND DEPOSIT-SLIP CABINET.

1,339,255.

Specification of Letters Patent.

Patented May 4, 1920.

Application filed August 29, 1918. Serial No. 251,875.

To all whom it may concern:

Be it known that I, GUY F. BRISENDINE, a citizen of the United States, residing at Decatur, in the county of Macon and State 5 of Illinois, have invented certain new and useful Improvements in Check and Deposit-Slip Cabinets, of which the following is a specification.

My invention relates to improvements in 10 check and deposit slip cabinets particularly designed for use in connection with posting machines in banks, business houses and the like, the principal object of this invention being the provision of such a cabinet in 15 which the checks and deposit slips may be placed or held in a convenient position for handling, and when posted may be readily deposited in a proper compartment in regular order.

20 Further objects of this invention include the improvements in details of construction and arrangement whereby a simple and effective cabinet of the type described is provided.

25 To the accomplishment of the foregoing and such other objects as may hereinafter appear my invention consists in a construction, combination and arrangement of parts hereinafter described and then sought to be 30 defined in the appended claims, reference being had to the accompanying drawing forming a part hereof and which shows merely, for the purpose of illustrative disclosure, a preferred embodiment of my invention, it being expressly understood however, that various changes may be made in 35 practice within the scope of the claims without digressing from my inventive idea.

Figure 1 is a perspective view of the cabinet 40 showing the slide board and drawers open.

Fig. 2 is a plan view with the board and drawers closed.

Fig. 3 is a section taken on line 3—3 of 45 Fig. 2.

Fig. 4 is a section taken on line 4—4 of Fig. 2.

Fig. 5 is a detail vertical transverse section.

50 In all the views the same reference characters designate similar parts.

Referring now to the drawing the numeral 1 designates a standing table or the like, affording a supporting means for a 55 cabinet constructed according to my invention. This cabinet comprises the base part

2 in which are provided the plurality of drawers 3 and the sliding leaf 4. The top member 5 of this base part forms a bottom for the upper part, or receptacle, 6 of the 60 cabinet.

This upper part 6 of the cabinet is substantially rectangular in horizontal cross section and is provided with a longitudinal partition 7 dividing it into two compartments of unequal width. On top thereof and one side of the partition I provide a receiving tray, or bin, 8, which has the inclined bottom 9 and the inclined front end 10 provided with the opening 11 therein to 65 facilitate the removal of the checks or other articles held in the tray or bin. It is to be noted that the bottom member 9 extends over the front wall of the upper part of the cabinet and that the opening 11 extends 70 partly in through the bottom member 9. The checks or other articles are held in place on the inclined bottom of the tray or bin 8 by means of the resilient member or spring 12. To the rear of this tray, or bin, 75 10 provided the opening 13 leading into a chute 14 formed by the inclined wall 15 by which the checks or other articles are directed into the larger receiving compartment 16. The lower end of the inclined wall 80 15 rests upon a transverse partition 15'.

On the other side of the upper part of the cabinet I provide a similar tray or bin 17 having the inclined bottom 18, the bottom extending over the front wall of the upper 90 part of the cabinet and being provided with the opening 20 which extends through the front end to facilitate the removal of the articles in this bin 17, these articles being deposit slips or the like and being held in 95 place, if desired, by the spring or other resilient means 21. To the rear of this tray or bin, 17, I provide the opening 22 leading to the chute 23 formed by the inclined wall 24 which discharges the deposit slips or other 100 articles into the smaller receiving compartment 25. The lower end of the inclined wall 24 rests upon a transverse partition 24'.

Each of these compartments 16 and 25 is provided with glass doors or windows 26 removably mounted in the sliding guide members 27 so that the articles in the compartments may be inspected and may be readily removed. In order to facilitate the proper positioning of the articles in the compartments I utilize a spring 28 shown in the larger compartment 16 which is positioned 105 110

near the front of the compartment and has the enlargement or hump 28' so that the front edge of the check or other article being discharged through the chute will engage it and will be thrown back into its proper position in the compartment and on the checks or other articles preceding it. This spring member may be utilized in connection with the smaller compartment for 10 the deposit slips or other articles.

It is to be noted that on one side of the upper part of the cabinet I provide a bracket or support 29 which may be utilized for an ink well or sponge cup or the like. Also 15 the top member of the base part of the cabinet is extended as at 30 and provided with a flange 31 to receive pencils, pens, erasers and other articles. It is also to be noted that in the rear of the upper part of the 20 cabinet I provide an open bin 32 which may be utilized for receiving unhonored checks and the like, as desired.

As stated hereinbefore this cabinet is designed for use in connection with posting 25 machines. The unposted checks are arranged in the bin 8 and held in place by the spring clip and the deposit slips are arranged in the bin 17 and may also be held in place by a spring. As the articles are 30 posted they are removed one by one and dropped into the chute through which they will be discharged into their proper compartments and into their proper positions therein, making the cabinet a very desirable 35 and efficient adjunct to the equipment of banks, business houses and the like, utilizing posting machines. The drawers may be utilized for any suitable supplies such as balance sheets and the like. The cabinet 40 may be made of wood, the various parts of metal, or the same may be made entirely of metal or composition, if desired.

What I claim is;

1. A cabinet of the character described including in combination a receptacle divided 45 into two compartments, a tray for each compartment, a chute located to the rear of each tray leading to one compartment, and means in one compartment for positioning the articles as they drop from said chute therein, said means including a resilient member depending vertically from the top wall of said compartment and adapted to engage the front edge of the articles as they are discharged therein from said chute.

2. A cabinet of the character described including in combination a receptacle having a longitudinal partition dividing the same into two compartments, a tray located over 60 each compartment and each having an inclined bottom and an inclined front end with an opening in the front end and extending partially into the bottom, the bot-

tom of said tray extending slightly over the front wall of said receptacle, and a chute 65 located at the rear of each tray and leading to each compartment, and removable glass doors for each compartment.

3. A cabinet of the character described including in combination a base member having 70 a plurality of drawers, an upper part positioned on said base member comprising a receptacle having a longitudinal partition dividing the same into two compartments, a tray for each compartment, each tray having an inclined bottom and an inclined front end, said bottom extending slightly over the front wall of said receptacle, and said front end having an opening therein which extends slightly into the inclined bottom of 75 each tray leading to its compartment, and resilient means in said tray for holding the articles in position.

4. A cabinet of the class described, comprising side, rear and front walls, the side 80 and rear walls being higher than the front, a longitudinal partition, transverse partitions between said longitudinal partition and the side walls, chute bottoms disposed in an inclined relation with their lower ends 85 on said transverse partitions and their upper ends on said rear walls, tray bottoms disposed between said side walls and longitudinal partition with their front ends projecting over the front wall and in a spaced 90 relation to said chute bottoms providing chutes opening at the rear of the trays, the trays being provided with front walls having vertical openings therein, the edges of the bottoms having notches registering with 95 said openings facilitating the fingering of the articles in said trays.

5. In a cabinet of the class described, the combination of a tray, a receptacle disposed below said tray, a forwardly directed chute 100 having its mouth at the rear of said tray, and a positioning member depending into said receptacle in position to be engaged by the articles delivered from the chute and having a rearwardly projecting stop with 105 which the front edges of the articles engage temporarily supporting the same, for the purpose specified.

6. In a cabinet of the class described, the combination of a tray, a receptacle disposed 110 below said tray, a forwardly directed chute having its mouth at the rear of said tray, and a stop arranged in said receptacle in position to be engaged by the front edges of the articles delivered from the chute temporarily supporting the same and permitting 115 their rear ends to proceed as they fall to position in the receptacle.

In testimony whereof I hereunto subscribe my name.

GUY F. BRISENDINE.
